UNITED STATES PATENT OFFICE.

ISAAC B. KLEINERT, OF NEW YORK, N. Y.

DRESS-SHIELD.

SPECIFICATION forming part of Letters Patent No. 460,825, dated October 6, 1891.

Application filed March 30, 1891. Serial No. 386,995. (No specimens.)

To all whom it may concern:

Be it known that I, ISAAC B. KLEINERT, a citizen of the United States, residing at New York, in the county of New York and State of New York, have invented certain new and useful Improvements in Dress-Shields, of which the following is a specification, reference being had therein to the accompanying drawing.

10 This improvement relates more particularly to that class of shields which are formed of textile fabric lined with rubber; and the invention consists in the peculiar construction, arrangement, and combinations of parts hereinafter more particularly described and then definitely claimed.

15 The accompanying drawing shows a perspective view of a dress-shield constructed according to my improvement, with one corner 20 turned up to show portions that would otherwise be hidden.

25 In the ordinary dress-shield as commonly made the curved shape causes the portions of the edge about midway between the highest and lowest parts to curl over and lie in wrinkles, thus leaving a part that should be 30 protected uncovered, besides injuring the wrinkled part of the shield and causing an uneasy feeling to the wearer owing to the 35 wrinkle. To avoid this is the object of my invention, which I accomplish by making the sides and bottom of the shield substantially 40 straight and preferably square, as shown.

45 In carrying out my invention I take two pieces of textile fabric A, (preferably woven,) each having three of its edges substantially straight and two of them preferably at right angles to the bottom one, and its upper portion curved in the usual form of the tops of 50 dress-shields. These curved portions are united in any suitable way, but preferably by sewing, and their edges may be bound or hemmed, as desired, as shown at a. Between the two pieces I then set a double layer B of rubber or other approved water-proof material of the ordinary dress-shield shape, which I generally secure therein by sewing each layer to that part of the textile fabric nearest it by a line of sewing C, thus making a lining 55 of water-proof material of the ordinary dress-shield shape and size. This lining of water-proof material may be made of one piece, or

of two pieces joined at the curved edge, but preferably of a single piece, and it may be united by cement to the textile fabric or not, 55 as desired, or be formed by coating the fabric in any known manner, to suit the taste of dealers or users. By this arrangement the entire surface of the shield covered by the water-proof lining is caused to lie flat, and 60 thus the corresponding surface of the dress covered by the water-proof lining is bound to be reliably protected, the injury to the shield prevented, and discomfort to the wearer avoided. Another advantage is that the edges 65 can be seamed securely into the seams of the waist without necessitating the puncturing of the body of the dress by the line of stitching around the curve of the dress-shield, which 70 stitches must of necessity be very slight and therefore insecure, so that they are apt to break away, thus leaving the shield in a condition likely to be displaced by the motion of the body.

75 I do not limit myself to the exact shape shown, as the bottom may be slightly curved, or the bottom may be rather narrower than the top without departing from the spirit of my invention. Nor do I limit myself to a woven fabric, as stockinet may be used, if 80 preferred, in which case I should prefer to make the textile fabric without seam at the inner curve and formed into shape in the usual manner; but in this case it would be advisable in the practical manufacture to 85 make the protected part of the shield in the usual manner and then stitch onto it pieces to make the sides and bottom square. It may become a matter of economy in ordinary bound shields to have the squaring-piece 90 separate; and, again, in expensive silk shields it may become a matter of strength as well as economy to attach to the silk shield proper a squaring piece of cotton fabric.

95 I am aware of the English Patent No. 17,721, of 1888, in which shields are shown with substantially straight edges; but in this case the water-proof material covers the entire shield. I am also aware of the United States Patent No. 427,985, issued May 13, 1890, to Pierre P. 100 Guillaume, in which the shield is of the ordinary form, but is provided with an attaching edge. I consider my invention as essentially different from both of these and as hav-

ing advantages which neither of the subject-matters of the aforesaid patents possess, for while I prevent the edges coiling and wrinkling, I save much on the construction, and 5 am therefore enabled to provide a better and cheaper article at less cost.

What I claim as new is—

As an improved article of manufacture, a dress-shield comprising a covering A of textile fabric having its top edge curved and its side and bottom edges straight, and a waterproof lining of double-crescent shape, of 10 smaller size than said covering, and having

its concave curved edge fitting under the curved edge of the covering and its convex 15 curved edges attached to the inner sides of the same at a distance from the straight edges, all substantially as herein shown and described.

In testimony whereof I affix my signature in 20 presence of two witnesses this 28th day of March, 1891.

ISAAC B. KLEINERT.
